UNITED STATES PATENT OFFICE

2,329,740

MACHINE FOR FORMING HEEL SEATS

Edward H. Bastable, Newton, Mass.

Application October 2, 1941, Serial No. 413,315

6 Claims. (Cl. 12—31.5)

The invention relates to an improved method of and means for forming upon the heel portion of a sole a heel seat to receive different types of heels to be attached.

Heel seat trimming machines of the prior art usually embody a cutting tool operative to bevel off a U-shaped strip and another cutting tool to sever the strip from the heel portion of a sole, the line of cut of the severing operation being along the breast line and substantially at right angles to the plane of the sole, thereby providing a U-shaped convexity terminating at its inner ends in abutments against which the inner edge of a heel may be positioned, as illustrated in United States Patent No. 1,307,284.

Where the heel seat has been accurately cut to receive a particular size and type of heel, such machines are generally satisfactory, but when inaccuracies are encountered, either in the shaping of the heel cavity or in the formation of the heel seat, it is extremely difficult to obtain an accurate fit because the abutment produced by severing the U-shaped strip either provides a gap, if the heel should be moved outwardly to correct position, or prevents the heel from being moved inwardly to correct position, thereby producing a rearwardly offset fit. In either case the inaccurate fit not only detracts from the appearance of the finished shoe, but also is apt to weaken the construction.

The principal objects of the present invention are to provide an improved shoe construction and method of making the same which overcomes the aforementioned objectionable features, and to provide a heel seat trimming machine which is of simple design and of strong and durable construction and which is efficient and reliable in operation, capable of accurately operating upon right and left soles to form a heel seat upon which heels of different styles and types may be accurately fitted.

Further objects relate to various features and will be apparent from a consideration of the following description and the accompanying drawings, wherein:

Fig. 1 is a top plan view of a machine constructed in accordance with or embodied in the present invention;

Fig. 2 is a side elevation thereof;

Fig. 3 is a section on the line 3—3 of Fig. 1;

Fig. 4 is a section on the line 4—4 of Fig. 2;

Fig. 5 is an end elevation of the machine;

Fig. 6 is a perspective view illustrating the manner in which a sole is positioned within the machine prior to the cutting operation;

Fig. 7 is an enlarged section illustrating the side beveling operation;

Fig. 8 is an enlarged fragmentary perspective view illustrating the manner in which both cutting or beveling operations are performed;

Fig. 9 is a perspective view of the heel portion of a sole after being operated upon;

Fig. 10 is a side elevation illustrating the manner in which a heel may be adjustably applied to a heel seat formed in accordance with the present invention;

Fig. 11 is a perspective of an outsole formed with a heel seat to receive a Louis or French heel;

Fig. 12 is a fragmentary side elevation, with parts shown in section, of a shoe having a Louis heel;

Fig. 13 is a fragmentary perspective view of an outsole formed with a heel seat to receive a Cuban heel; and

Fig. 14 is a side view illustrating the rear portion of a shoe having a Cuban heel.

Referring to Figs. 1 to 8, the machine shown therein comprises a generally rectangular base member 1 adapted to be received by or secured to the work rest a slidble bed of a conventional press (not shown) such as is used in stamping or cutting out shoe upper sections or the like, the base being constructed so as to provide a housing for certain parts of the operating mechanism hereinafter described. The rear portion of the base supports a plurality of upstanding posts 2, the upper ends of which project into openings formed in a head member 4, and compression springs 5, circumscribed about the posts 2, normally support the head 4 at a predetermined level above the base, these posts being arranged to provide an operating zone or area to receive the end of a sole to be operated upon.

The front of the head is recessed, as indicated at 6 (Fig. 1), and its center is formed with a slot 7 which receives a screw 8 for adjustably holding the block 9 to which a U-shaped cutter blade or knife 10 is suitably secured. Mounted upon the base 1 beneath the cutter 10 is a die block 11 formed with a U-shaped groove 12 to receive the cutting edge of the knife or blade 10 when brought into operative position. As shown in Fig. 7, the portion of the cutting block surrounded by the groove 12 is formed with a convex surface so that in the cutting operation the sole S is bent or so distorted that the knife 10 cuts into it at an angle relative to the plane of the base, thereby producing a bevel cut.

As shown in Figs. 2, 3, and 5, the head 4 and

knife 10 are normally held by springs 5 in spaced relation to the cutting block 11 which is adjustably secured to the base 1 by a screw 14. By loosening the screws 8 and 14, the cutter knife 10 and block 11 may be adjusted as desired, and by disengaging the screws both the cutter and block may be removed and replaced by similar cutting instrumentalities of different size or design. In any case, the construction and design of the machine is such that downward movement of the head 4 carries the movable cutter 10 into operative engagement or relationship with the block 11, the downward movement of the head being limited by upstanding abutments 15 (Figs. 5 and 6) which provide stops carried by or formed integral with the base 1.

A pair of spaced guide blocks 18 is mounted on the base 1 forwardly of and in alignment with the stops 15, and both the stops and guide blocks are formed with axially aligned openings extending at an angle of the order of 20° to the plane of the base. These openings receive guide posts 20 which slidably support knife carriers 22 and compression springs 21, circumposed about the posts, normally hold the carriers in retracted position, as shown in Figs. 1 to 3. The carriers 22 are generally U-shaped, as shown more clearly in Figs. 4 and 5, so that their outer legs enter the openings in the guide blocks while their inner legs extend rearwardly and downwardly toward the inner end of the groove 12 in the cutting block 11.

Cutting or severing knives 25 are removably and adjustably secured to the carriers 22 by screws 26 so that when these knives are carried downwardly to the limit of their cutting stroke their beveled cutting edges are contiguous to the inner ends of the knife 10 when the latter has likewise been carried to the limit of its cutting stroke. In order to avoid interference with the knives 25, the inner ends of the knife 10 may be cut away, as shown at 27 in Fig. 8. In order to insure a complete severing of the marginal portion of a sole by a smooth, clean cut, the inner edges of the knives 25 may, if desired, be provided with cutting ears 28, although it is to be understood that the shape of the inner end of the knife 10 and the adjacent end of the knives 25 may be otherwise than as here shown so long as they are operative to insure severing of the marginal portion of the heel.

The knives 25 are operated in timed relation to the knife 10 and in response to downward movement of the head 4, and to this end the front portions of the head on each side of the recess 6, are provided with depending posts 30 (Figs. 1-3), the lower ends of which carry screws 31 provided with lock nuts 32 by means of which the effective lengths of the post 30 may be varied. Within the housing provided by the base 1 is a pair of aligned, transversely extending shafts 35 suitably supported in bearing members formed integral with or carried by the base. Each shaft 35 supports a rocker arm 38 one end of which is connected by a pin 39 with a bell crank 40 also mounted on the shaft 35. The free end of arm 38 extends beneath the post 30 and the free end of the bell crank 40 projects upwardly to a position adjacent to the outer end of the carrier 22 which is formed with a rounded or cam-like surface 41.

The parts are so constructed and arranged that normally the end of the arm 38 contacts the adjacent screw 31 of the post 30, and the end of arm 40 contacts the end 41 of carrier 22, as

shown in Figs. 2 and 3, and hence cutting movement of the carriers 22 is initiated substantially simultaneously with downward movement of the head 4. If desired, the screw 31 may be adjusted so as normally to be held in a predetermined spaced relation to the end of arm 38, and in this manner the cutting movement of the carriers and the extent of such movement may be varied to suit the requirements of the case. In any event, downward movement of the head 4 effects the cutting movement of the knives 10 and 25, and as the head continues its downward movement, the cutting edge of the knife 10, due to the construction and arrangement of parts, first strikes a sole S (Fig. 8) positioned on the cutting block 11, and as the knife 10 is cutting into the sole, the severing knives 25 commence their cutting action on the sole. When the knife 10 has been carried through the sole, it continues a short distance into the groove 11 and by this time the knives 25 have been forced through the sole, thus severing the U-shaped marginal strip by a transverse bevel cut. Although the commencement and finishing of the cutting operations are preferably sequential, yet as a practical matter they occur so quickly as to be substantially simultaneous.

The advantage of having the commencement of the cutting operations sequential resides in the fact that the knife 10, first striking the sole S, tends to hold or clamp it in fixed position during the cutting operation about to be performed by the knives 25, whereas if the reverse were the case, the knives 25, due to their angular movement, would tend to dislodge the sole from its proper position. Thus, the knife 10 performs a dual function, viz., cutting the U-shaped marginal strip and serving positively to hold the sole during the cutting operation performed by the knives 25.

In order properly to position both right and left soles on the block 11, any suitable type of gauges may be provided. Since it is desirable that a machine of this type should be able to operate not only on right and lefts, but also upon different sizes and styles, the gauge means should be adjustable so as to accommodate such requirements. Moreover, the accuracy of the operation is of course dependent upon the accuracy with which such gauges are set, and hence it is equally desirable to provide means for insuring an accurate setting of the gauges. To this end, I provide a template T (Fig. 6) preferably formed of sheet metal having the exact size and shape of the trimmed sole desired, the template being used in conjunction with a pair of gauge setting fingers 45 which are carried by the head 4.

The fingers 45 are formed integral with a flat body member 46 having a vertically extending slot 47 (Fig. 3) through which a headed set screw 48 projects, the set screw serving to clamp the gauge setting device against the recess edge of the head 4, as shown in Figs. 1 to 3. The construction and arrangement of parts are such that when the device is lowered the ends of the fingers 45 are contiguous to the die block 11 at a point adjacent to the ends of the groove 12 (Fig. 6), a position corresponding to the breast line of the template T and sole S (Fig. 8). Thus, the fingers 45 determine the inner limit to which a sole should be inserted and hence provide a setting against which the shoulders of the template T should engage for proper setting of the cooperating gauge members 50.

The gauge members 50 comprise a plate 51 slid-

ably mounted on the face of the base 1, the plate being formed with a pair of V-shaped notches 52 and 52^a which receive the toe end of the template or sole. The plate 51 is secured to a carrier member 54 formed with a transversely extending slot 55 and a longitudinally extending slot 56. Set screws 51 and 58 project through these slots into the base 1 and serve to lock the gauge in any desired position of lateral and/or longitudinal adjustment.

The gauge 50 also cooperates with another gauge 60 which comprises a transversely extending screw shaft 61 suitably mounted for rotation in the base 1, as shown more clearly in Fig. 6. The outer end of the screw shaft 61 carries a thumb wheel 62 and its inner end carries a screw threaded lug 64, slidably mounted in a slot 65 formed in the base 1 so that the lug 64 may be carried inwardly or outwardly upon rotation of the screw shaft in one direction or the other. The lug 64 projects upwardly above the surface of the base so as to provide an abutment or stop against which one edge of the instep or shank portion of a sole may engage. In this manner the lug 64 cooperates with one or the other of the notches 52, 52^a to determine the correct position of a sole about to be trimmed by the knives 10 and 25. In order to lock the gauge 60 in adjusted position, a latch member 66 (Fig. 4) is mounted on the base and by means of a pin and slot arrangement 67 the end of the latch 66 is movable into and out of engagement with the thumb wheel 62. A set screw 68 is provided to clamp the latch member 66 in locking position.

To set the gauges correctly for a given size or style of outsole to be trimmed, a template T having the exact size and shape of the finished sole is first inserted so that the shoulders at the breast line of the template engage the fingers 45, as illustrated in Fig. 6. As here shown, the template T may correspond to a right sole for use with a French heel, and in such case the gauge 50 is adjusted so that the toe portion of the template projects into the notch 52, as shown by the full lines of Fig. 6; but if the template T' corresponds to a left sole, then the gauge 50 is adjusted so that the toe portion of the template projects into notch 52^a, as shown by the broken lines of Fig. 6. With the template properly positioned, the gauge 60 is adjusted so as to bring the stop or lug 64 into engagement with its shank edge, and the gauge 60 may then be locked by the latch member 66. The gauges 50 and 60 are now adjusted to hold a sole in proper position for operation by the cutting knives 10 and 25, and hence the gauge setting fingers 45 may be elevated to a position above the operating zone, as shown in Figs. 1 and 3, and locked in such position by screw 48.

The machine above described may be used in conjunction with a press of the type shown in U. S. Patent No. 1,886,554, and in order to secure it to the bed of the press, the base 1 is provided with brackets 68 which carry screws or like fastening elements for holding it firmly in position. The adjustments above described may be made before or after the machine is inserted in the press and other adjustments, as well as replacements of parts, may be made while the machine is attached to the press, it being noted that the adjusting devices are conveniently located so that it is unnecessary to remove the machine in order to make replacements and adjustments.

After having made the aforementioned ad-

justments, the machine is then ready for operation as follows: A rounded sole S to be trimmed is inserted in the operating zone so that its shank edge abuts the gauge member 64 and its toe portion fits against one of the V-shaped notches. Where a sole to receive a French heel is to be prepared, the usual flap splitting or skiving operation is first performed in the conventional manner, and with the breast flap held out of the way 10 the sole is inserted grain side up. On the other hand, if the sole is to receive a Cuban heel, the splitting operation is dispensed with and the sole inserted grain side down. When positioned as described above, the rear portion of the sole is correctly located on the die block 11 and operation of the press brings the head 4 downwardly so that the knife 10 cuts through the heel portion of the sole and substantially simultaneously the severing knives 25 operate to remove the U-shaped strip from the margins of the heel portion. The trimmed sole is then removed, another sole inserted and the operation repeated.

Referring to Figs. 9 to 12, the trimmed sole S 25 is to receive a French heel, and it will be observed that the heel seat 70 is defined by a U-shaped bevel cut 71, the ends of which adjoin the transverse inwardly directed beveled surfaces 72 which terminate in feathered or tapered end portions 30 located rearwardly of the breast line 74 of the sole. The sole S is applied to a lasted shoe in the usual manner, and a French heel H is then positioned so that the outer ends of its breast edge are seated on the beveled surfaces 72, as shown 35 in Fig. 10, in which position the rear or outer surface of the heel should merge into the contour line of the rear of the shoe, as shown in Fig. 12. In the event that the heel should be adjusted forwardly or rearwardly in order to attain the correct fit, it is merely necessary to slide the breast edge of the heel along the bevel surface 72, it being noted that these surfaces have sufficient breadth (being of the order of $1/4$ " or more) to accommodate the maximum adjustment to insure an accurate fit. After having secured the heel in position, the breast flap 75 may then be cemented in place in the customary manner and the shoe is then ready for the usual finishing operations.

50 It should be noted that due to the contour of the heel cavity the outer ends of its breast edge bow inwardly and are firmly seated on the bevel surfaces 72 and hence provide a substantially continuous surface over which extends the breast flap 75. Even though inaccuracies or variations in forming the heel seat or in applying the outsole to the lasted shoe should be encountered, it will be observed that such may be compensated for or overcome by adjusting the heel in one direction or the other, as indicated by the broken lines of Fig. 10, thus avoiding a hand-trimming operation or the production of a gap between the breast line of the sole and the heel, which would not only detract from the appearance of the shoe, but also tend to weaken the construction.

In preparing a sole to receive a Cuban heel H' (Fig. 14), the rounded sole S' is inserted in the machine in the same manner as above described except that the grain surface is down and hence the bevel surfaces 72 extend from the inner or flesh surface rearwardly to the outer or grain surface, terminating in a feathered edge located rearwardly of the breast line 74' of the sole, as illustrated in Fig. 13. The sole is applied to a lasted shoe in the usual manner and the Cuban

heel H' is applied in a manner similar to that above described, it being noted that the outer ends of the breast edge of the heel are seated on the outer or grain surfaces of the bevel portion 72', as shown in Fig. 14. Due to the tapered or beveled portions 72', the edge line of the outsole merges with that of the heel and hence presents a more attractive appearance as compared with prior art constructions wherein the edge of the outsole abuts the breast surface of the heel and hence does not present a continuous edge line effect.

Another feature of the invention resides in the fact that the usual rasping operations, invariably found necessary to round and level off the floating ends of the shank portion of a sole trimmed in accordance with prior art practices, is minimized if not eliminated since such ends are firmly anchored beneath the marginal portions at the breast line of the heel when the outsole is prepared in accordance with the present invention.

I claim:

1. A heel seat fitting machine comprising means for supporting a sole in a predetermined fixed position, cutting means for making a substantially U-shaped cut through the marginal heel portion of the sole, and severing means mounted to move at an angle to the path of travel of said cutting means and to the supporting means for the sole so as to sever said marginal heel portion by transverse bevel cuts, the ends of which are located rearwardly of the breast line of the sole.

2. A heel seat fitting machine comprising means for supporting a sole in a predetermined fixed position, cutting means for making a substantially U-shaped cut through the marginal heel portion of the sole, and severing means operative concomitantly with said cutting means, said severing means being mounted to move at an angle to the path of travel of said cutting means and to the supporting means for the sole so as to sever said marginal heel portion by transverse bevel cuts the ends of which are located rearwardly of the breast line of the sole.

3. A heel seat fitting machine comprising means for supporting a sole in a predetermined fixed position, reciprocating cutting means for making a substantially U-shaped cut through the marginal heel portion of the sole, and severing means operative during the cutting stroke of said reciprocating cutting means, said severing means being mounted to move at an angle to the

path of travel of said cutting means and to the supporting means for the sole so as to sever said marginal heel portion by transverse bevel cuts the ends of which are located rearwardly of the breast line of the sole.

5 4. A heel seat fitting machine comprising a base having gauge means for holding a sole in a predetermined fixed position, a U-shaped cutter blade mounted for reciprocatory movement, actuating means for reciprocating said blade so as to make a U-shaped cut through the marginal heel portion of said sole, a pair of spaced shearing knives mounted for reciprocatory movement at an angle to the plate of the sole and to the path of travel of said cutter blade, said knives being positioned so as to sever said marginal heel portion by transverse bevel cuts, the free ends of which are located rearwardly of the breast line of the sole, and means responsive to the operation of said actuating means for operating said knives.

10 5. A heel seat fitting machine comprising a base having gauge means for holding a sole in a predetermined fixed position, a cutter supported for reciprocatory movement toward and away from said base and operative to make a U-shaped cut through the marginal heel portion of the sole, a pair of spaced shearing knives mounted for reciprocatory movement at an angle to the path of travel of said cutter and to the plane of said base, said knives being operative to sever said marginal heel portion by transverse bevel cuts the ends of which are located rearwardly of the breast line of the sole, and actuating means for reciprocating said cutter and knife substantially simultaneously.

15 6. A heel seat fitting machine comprising a base having a gauge means for holding a sole in a predetermined fixed position, a head member mounted to reciprocate toward and away from said base, a cutter secured to said head and operative to make a U-shaped cut through the marginal heel portion of the sole, a pair of spaced shearing knives mounted for reciprocatory movement at an angle to the plane of the base and positioned to sever said marginal heel portion by transverse bevel cuts the ends of which are located rearwardly of the breast line of the sole, and mechanism operatively associated with said knives and having parts engageable by means carried by said head member for reciprocating said knives during movement of said head member toward said base.

EDWARD H. BASTABLE.
